CLAIM

We claim the ornamental design for a tire, as shown and described.

DESCRIPTION

FIG. 1 is a front, left and top side perspective view of a tire showing our new design;
 FIG. 2 is a rear, left and top perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof; and,
 FIG. 9 is a partial enlarged view thereof.
